Application August 10, 1926, Serial No. 128,492

22 Claims. (Cl. 250—16)

My invention relates to electrical distribution and more particularly to the interconnection of the various instruments and parts pertaining to a radio receiving or transmitting apparatus, although not limited to such application but also applicable to other group connection of electrical devices.

In the present invention there is contemplated the standardization of electrical assembly, particularly that of radio apparatus, by eliminating the usually complicated system of cross wiring, providing for the automatic by-passing of high frequency currents, the elimination of objectionable "feed back" effects and facilitating the speed and rapidity of assembly and construction of such apparatus.

In its preferred embodiment the invention comprises a combined distributor and condenser strip consisting of a plurality of separate electrical conductors arranged in parallel spaced relation, and preferably embedded in a body of dielectric or insulating material, by which the multi-conductors will be maintained in a fixed relation in a unitary group assembly but disconnected one from another. The several conductors are provided at spaced intervals with outlet connections or attachment lugs for connection with various electrical instruments or devices. These electrical taps or outlets of the several conductors comprising the group assembly, are arranged in a predetermined sequence or grouped relation so that at any selected point throughout the length of the multiple conductor strip there will be conveniently and closely located a tap or outlet to each of the component conductors. The multi-conductors are preferably thin flat strips of sheet metal although they may be given other forms to facilitate manufacture, economize production, and to conform to various conditions of usage. In the present method of manufacture, these metallic conductor strips are separated one from another by interposed strips of fabric impregnated with phenolic condensation material or other material possessing insulating and dielectric properties. The assembly is then permanently united, preferably though not necessary, under the influence of heat and pressure to form a unitary strip or body in which the conductor strips are fixedly embedded in parallel spaced relation with their spaced taps projecting beyond the enclosing body.

The convenience of this multi-conductor strip for distribution of electrical current and group interconnection of a number of instruments or devices is, however, more or less subordinate to

the intercapacity electrical effect afforded by the superposed spaced conductor strips which form a fixed by-pass condenser for all alternating currents whether radio or audio frequency or alternating filament current, at any point in the receiver or transmitter. The impedance and effective capacity of the multi-conductor unitary assembly may be accurately measured. Such effective impedance and capacity then becomes a known factor in the calculations incident to efficient designing of radio and other electrical apparatus. The accurate measurement of these capacity and impedance factors of the usual radio set wiring has heretofore been impossible.

One of the objects of the invention is to eliminate the usual unsystematic wiring and to reduce to minimum both in number and lengths all connection and leads carrying electrical current of the various characteristics and frequencies found in radio receiving or transmitting apparatus. There are thus reduced or removed the collateral effects of such leads and connections one upon the other with the further and important result of entirely eliminating many of the common causes and minimizing other causes of harmful "feed back" effects.

A further object and achievement of the present invention is to enable the use of mathematical precision and measurement to calculate and determine the effects of changes and variations in radio apparatus design and construction, or the like, by placing directly across the battery or other current supply circuit and other circuits a high capacity condenser the capacity and impedance values of which are definitely known and remain fixed.

A further object of invention is to enable the use of modern production methods in the manufacture of radio and other electrical apparatus thus insuring duplication and identity of results by providing for connection of instruments and parts without the use of wires by the use of conveniently located taps arranged in predetermined grouped relation at convenient intervals.

A further object of invention is to provide an improved assembly unit by which capacity and impedance effect may be ascertained and controlled and in which these effects may be varied at will by utilizing the grouped conductors in different sequence or relationship, and by providing such conductor strips in different numbers, thus allowing a choice of widely or closely spaced individual strips for specific purposes with corresponding variations of capacity and impedance effect.

A further object of invention is to provide such approved form of distributor-condenser capable of production in stock lengths to be subsequently cut to size as needed, or to be formed 5 in sections or units to be joined one to another to afford a distributor-condenser element of required size.

With the above primary and other incidental 10 objects in view as will more fully appear in the specification, the invention consists of the features of construction, the parts and combinations thereof and the mode of operation, or their equivalents as hereinafter described and set forth in the claims.

15 Referring to the accompanying drawings wherein is shown the preferred but obviously not necessarily the only form of embodiment of the invention, Fig. 1 is a perspective view of a simplified form of the assembled distributor-condenser or by-pass strip forming the subject hereof. Fig. 2 is a detail perspective view showing 20 a portion of the strip shown in Fig. 1 separated into its component parts. Fig. 3 is a plan view somewhat diagrammatic showing the assembly 25 of a radio receiving set utilizing the present distributor-condenser unit for interconnecting the several parts.

Fig. 4 is a plan view of the conductor-condenser strip in a form for commercial production. A series of sockets, a potentiometer, rheostat, resistance unit, transformers, and phone 30 jack, have been shown interconnected by the distributor-condenser device.

Fig. 5 is a plan view of one of the individual 35 strips. Fig. 6 illustrates the use of the device in conjunction with variable condenser plates. Fig. 7 is an enlarged transverse sectional view. Fig. 8 is a detail plan view partly broken away. Figs. 9, 10 and 11 illustrate different sequence or 40 combinations in which the conductors may be employed.

Like parts are indicated by similar characters of reference throughout the several views.

While regeneration or "feed back" is quite a 45 desirable factor in some forms of radio apparatus if properly controlled, but the promiscuous "feed back" or transfer of electrical energy from one part of the circuit or apparatus to another is the cause of much inefficiency, distortion, and 50 undesirable operation of radio apparatus. It is almost impossible to determine the inter-capacity effects of numerous small wire connections of the radio apparatus many of which extend parallel to each other and within the fields of 55 condensers and transformers and the impedance effect of long leads, soldered joints, or loose connections. It is to overcome this unknown factor which differs materially in every set or apparatus although apparently constructed according to the same plan; and in order that these 60 capacity and impedance factors may be reduced to measurable values and maintained in certain known limits, and objectionable "feed back" effects or transfer of energy from one part to another minimized, that the present form of distributor-condenser unit has been developed.

In the present device there is contemplated a simple efficient group connector having definitely known capacity and impedance factors, which 70 will be mechanically strong and rugged to withstand shipping, handling and hard usage, and which will possess a neat appearance and afford a safe guard against mistakes in wiring and accidental short circuits with their incidental 75 destruction and injury to tubes and batteries

and which will further more possess a wide degree of adaptability to a large number of different circuits and forms of apparatus. Considered electrically the device is designed to diminish inductance in the battery circuits and hence the creation of less external fields, and less radio frequency activity across leads and between parts of the apparatus. The by-pass 10 effect afforded by the increased capacity lowers the radio frequency voltage and eliminates much objectionable feed back or undesirable transfer of energy. The reduction of external fields minimizes the ability to pick up radio frequency energy from adjacent apparatus and thereby eliminate much interference.

The distributor-condenser strip or element forming the subject matter hereof comprises a series of independent strips 1, 2, 3, 4, and 5 of electroconductive material superposed one upon the other in parallel spaced relation and separated by intermediate strata 6 of dielectric or insulating material. There may be any number of such superposed strips incorporated in a distributor-condenser unit. Some of these strips subsequently may be connected in pairs by the 20 constructor to increase capacity effects or intermediate strips may be grounded to eliminate capacity effects. The series of conductive strips 1 to 5 inclusive are of identical construction and are provided at spaced intervals with marginal 25 tabs or ears 7. Although in Figs. 1 to 3 the tabs or ears 7 are located on one margin only of each strip, for commercial production they are preferably duplicated on opposite margins of the strips as shown in Figs. 4 and 5. Such tabs or ears 7 30 serve as tabs or outlets for electrically connecting the conductor strip with various instruments or devices. To facilitate the assembly of the series of such strips and to more securely embed them in a body of insulating material, the strips are 35 preferably perforated at spaced intervals as at 8, through which the succeeding strata of insulating material join as at 9. These perforations also facilitate the assembly of the strips with their 40 lateral tabs or ears 7 arranged in predetermined spaced sequence. This is effected by off-setting the strips longitudinally so that the perforation 8a of one strip will register with the perforation 8b of the next strip and 8c of the succeeding strip, etc., thus stepping the tabs 7 of each succeeding 45 strip longitudinally one space. The succeeding ears or tabs on the individual strips are spaced 50 sufficiently far apart to afford an intermediate space between each group of spaced tabs of the assembly. In the commercial product this space 55 between groups substantially agrees with the distance between the connections of the regulation or standard tube socket and other apparatus. If only a single series of ears or tabs 7 are provided the strips are alternated or part of them turned 60 one way and part the other so that their tabs 7 extend in opposite directions and will project from opposite margins of the finished distributor-condenser strip or element 10. While the several strips 1 to 5 are duplicates of each other, due to 65 their assembly in longitudinally offset relation to each other, the tabs or outlet connection 7 on opposite sides of the assembly are spaced in predetermined sequence. The sequence of spaced tabs 7 pertaining to the different conductor strips 70 is successively repeated throughout the length of the distributor-condenser element. Since each conductor strip is provided with a plurality of tabs or outlet connections 7 and the tabs or outlet connections of different strips are grouped in 75

spaced sequence all of such conductor strips are conveniently available for connection of instruments and devices at any point throughout the length of the distributor-condenser element. It is entirely optional with the constructor as to which of the several superposed strips 1 to 5 he will employ for a specific purpose. It is found most convenient to employ the two strips having their tabs or outlet connections 7 turned toward the same side in alternating spaced relation in Figs. 1 to 3 for the filament circuit or A+ and A- battery connections. At the same time the strips having their tabs or outlet connections 7 turned in the opposite direction in Figs. 1 to 3 and exposed in spaced sequence are employed for the B+45 and B+90 and C battery connections.

In the commercial form of the device illustrated in Fig. 4 it has been found most convenient to utilize the first and last tab or ear 7 of each group as the A+ and A- connections for the tube filament. The intermediate tabs 7 of each group are employed for the B+ and C battery connections. It is unnecessary to provide a special conductor in the unit for the B- connections since in any event such connections ultimately lead to the A-conductor. Since it is customary to use different B battery voltages as B+22½ B 45, and B 90, such individual conductor strips to be utilized for B battery circuits may be arranged with their tabs or ears 7 in registry or one directly above the other, in order to economize space and provide for the repetition of the groups of connections at more frequent intervals. In the event only one of the B+ ears or tabs 7 will be utilized at a given point, the remaining connections or ears 7 pertaining to the B battery conductors, which are found unnecessary at a given point, may be readily removed. The material being quite thin such protruding ears are easily clipped or torn off thus leaving only the particular B+ tab or ear 7 to be utilized.

As before mentioned and as shown in Fig. 4 the successive groups of outlet tabs 7 are duplicated upon the opposite margins of the distributor-condenser unit 10. This not only enables the convenient connection of instruments or parts located on either side of the distributor-condenser strip 10 but it also accommodates instruments or parts of various sizes which may overlap the distributor-condenser strip to greater or less extent. In addition to facilitating the connection of instruments or parts at widely spaced opposite points such instruments or parts may be connected at points intermediate the ears 7 by bending such ears backwardly over the top of the insulating body. To this end the unit or strip 10 is provided at spaced intervals with holes 11. These holes 11 are concentric with the perforations 8 of the several conductor strips 1, 2, 3, 4, and 5. The holes 11, however, are contained only in the insulation or dielectric material protruding through the perforations 8 of the several strips and serving to join the strata of dielectric or insulating material one to the other. This relation of the hole 11 surrounded by a body of insulating material within the perforations 8 of the several strips is illustrated in Fig. 8, and in transverse sectional view in Fig. 7. The tab or ear 7 which is bent reversely over the body of the distributor-condenser unit is secured in its reversed position by a rivet or bolt 12 inserted through the hole 11 and through the perforation in the ear or lug 7. This bolt or rivet 12 may also serve to connect an instrument or a radio part or it may be utilized merely as a

binding post for a lead or conductor extending to such instrument. The manner of utilizing these outlet connections 7 for instruments of different sizes is illustrated in Fig. 4 wherein are shown three different sizes of transformers. The transformer 13 is of comparatively large size and extends across the distributor condenser unit and connects with the B+ and C tabs or ears 7 at the far side of the strip or unit 10. The opposite end of the primary coil of the transformer 10 is connected to the plate terminal of the tube socket 16. The opposite end of the secondary coil of the transformer is connected to the grid terminal of the succeeding tube socket 15. Thus by locating the transformers and tube sockets alternately or with the transformer immediately disposed between successive tube sockets the transformer coils may be directly connected at one end of the plate and grid terminals of the successive sockets while the opposite ends of such coils are directly connected to the proper outlet tabs 7 of the distributor condenser unit. At 15 in Fig. 4 is shown a small size transformer which is likewise connected with the grid and plate terminals of successive sockets, the opposite ends of such coil being directly connected with the B+ and C terminals 7 upon the near or adjacent margin of the distributor-condenser unit strip 10. Intermediate these two transformers 13 and 15 is shown a third transformer 14 of an intermediate size. The B+ and C terminals of this transformer extends too far over the distributor-conductor strip for direct connection with the tabs upon the near or adjacent margin as the transformer 15 is connected and they do not extend far enough for direct connection with the tabs at the far or extreme margin of the distributor-conductor strip 10 like the transformer 13. For the convenient direct connection of the transformer coils 14 with the distributor-conductor strip 10 the B+ and C tab or ear 7 are reversely bent over the top of the strip 10 and secured in such reversed position by the bolt or rivet 12 extending through the holes 11 which bolt or rivet may also serve to connect the end of the coils of the transformer 14. Thus various instruments may be conveniently connected either on the medial lines of the distributor-condenser strip 10 or beyond the opposite margins of such strip. There is shown at 17 in Fig. 4 a typical form of fixed resistance unit 17 which is extended transversely of the distributor-condenser unit or strip 10 and is connected to the A- ear or tab 7 at one side of such tab and to the F-terminal of the tube socket 16 at the opposite side of the strip. In such case the A- tab or ear on the margin of distributor-condenser unit or strip 10 adjacent to the F- terminal of the socket will be torn off or removed. This is also the case at 19 in Fig. 4 where the A- tab or ear 60 has been torn off or removed and the filament terminal of the tube socket 16 is connected by a short lead 20 with the rheostat 21 the opposite side of which is connected with the adjacent A- tab on the strip or unit 10. The phone jack 22 is connected directly to the B+ tab while the sleeve portion of the jack is connected to the plate terminal of the last socket of the series. Likewise in connecting a potentiometer as shown at 23 in Fig. 4 one terminal of the potentiometer 70 is connected to the A+ and another to the A- tab of the distributor-condenser strip or unit 10 while the intermediate terminal 24 of the potentiometer may be connected to a tab or ear upon a strip within the unit 10 to which is con-

nected the grid returns from transformers, etc.

It is entirely optional with the constructor of a radio apparatus which of the superposed strips he will use for a particular circuit or purpose.

- 5 For convenience of assembly the tabs 7 may be perforated for direct connection with the binding posts of tube sockets, transformers, rheostats and the like or such tabs may be utilized as solder connections for connecting the various 10 instruments and devices into the circuit. The constantly re-occurring tabs or outlet connections 7 on each conductor enable the direct connection of the various instruments and devices with minimum lengths of leads. It has been 15 found possible and practical by use of this distributor-condenser strip to build typical receivers of various types without the use of connecting wires or leads by direct connection of the instruments with the tabs 7. A typical method of 20 using the distributor-condenser unit heretofore described for the interconnection of the principal parts of a radio apparatus is illustrated in Fig. 3. A most convenient method of assembly is to mount the various instruments such as the tubes 25 or thermionic valves, transformers and inductance coils, resistive elements and the like upon a base or sub-panel and to mount the distributor condenser unit herein described on the under side of such sub-panel connecting it through the sub- 30 panel to the instruments above. Some of the instruments and devices, however, may be attached to the under side of the sub-panel overlying the distributor-condenser unit, which as before described is completely insulated except 35 the outstanding tabs or outlet connections 7.
- The judicious variation of the sequence in which the individual conductor strips are utilized affords a wide variety of effects. By adopting different conductor strips 1 to 5 for A and B battery 40 circuits various capacities and impedance effects can be thus achieved. The conductor strips for A and B battery purposes in the succession or relationship shown diagrammatically in Fig. 9 the A— conductor strip would have but little or 45 no capacity effect upon the B 45 conductor. If, however, this selection is made as indicated diagrammatically in Fig. 10 there would be an increased capacity effect between the A— and B+ conductor. By providing additional or surplus 50 interposed conductor strips and interconnecting strips in multiple as shown diagrammatically in Fig. 11 a maximum intercapacity effect can be secured or conversely by leaving certain intermediate conductor strips disconnected and unused 55 thereby increasing the spacing between active conductor strips or by grounding such intermediate conductor strip the intercapacity effect may be eliminated. The various capacity effects and conversely the impedance of the distributor-condenser element may be further varied 60 by making the conductor strips 1 to 5 of greater or less width, and as well of greater or less length. Instead of being strips these members for special electrical effects and to meet certain conditions of usage, may be formed as superposed plates. Such plates may be used as conductors for interconnecting various instruments or parts while at the same time the capacity effect may be increased and impedance decreased. Thus the element 65 possesses the material advantage that value of the capacity and impedance factor can be accurately and mathematically ascertained and be predetermined by such variations of size and of selection of the conductor members for particular purposes whereby certain selected con-

ductors may be more or less closely related in their assembly. The superposed closely spaced relation of the individual conductor strips embodied in the distributor-condenser unit enables one strip to shield the other, thereby preventing the creation of an external field and the elimination of "pickup" and radiating characteristics. This series of flat spaced strips confined in a small space is unable to cut many lines of force and the fields therebetween are concentrated 10 with no opportunity to radiate lines of force. Consequently no inductive pickup and throw-off effect occurs.

15 The distributor condenser unit herein described may form a part of the shielding of a radio set in addition to its other functions.

In addition to its function as a distributor for current, a by-pass condenser for high frequency current and elimination of undesirable feed back effect, and for shielding purposes, the unit strip 20 10 herein described may further form one part or element of a series variable condenser for tuning purposes. In all or nearly all radio sets one element or group of condenser plates as the case may be is grounded or connected ultimately through 25 various leads to the A— conductor. In the present case such A— conductor strip embedded in the unit may itself become such variable condenser grounded element and may furthermore be common to a plurality of variable elements. 30 Such a construction has been shown more or less diagrammatically in Fig. 6 wherein are shown the fixed conductor strips 1, 2, 3, 4 and 5 comprising the distributor-condenser unit 10 heretofore described. Associated with this distributor-condenser unit 10 are a plurality of movable plates 25 which are arranged for capacity effect with the unit 10. These plates 25 may be variously adjustable. In Fig. 3 two of the plates 25 are shown mounted for parallel movement in 40 a plane closely adjacent to and parallel with the unit strip 10. In Fig. 6 the several plates 25 are shown as capable of oscillatory movement toward and from the unit strip 10 thus affording a series of "book" type variable condensers. The variable plates 25 may be connected into different circuits as is shown in Fig. 3. However, the distributor condenser unit 10 is common to all of these condenser plates 25 which may be interconnected for unison adjustment or be independently 50 adjustable. Thus the distributor-condenser unit 10 eliminates entirely the wiring connections to one side of the series of variable condensers, and results in greatly confining the fields surrounding such condensers.

55 The term battery currents herein mentioned is to be construed as meaning supply for filament, anode and grid biasing purposes from whatever source, whether battery, power lines, or other source and is not limited to battery sources alone. 60 The terms "A battery," "B battery" and "C battery" are used merely for illustrative purposes and to agree with general usage, but with no intention to limit the application or scope of the invention. These terms are to be construed as including the 65 use of battery "eliminators" and other direct sources of current supply other than batteries.

Duo-functional condenser conductor unit or a duo-functional connector is used in the claims to 70 designate an element used for conducting an electric current from one portion of a circuit to another wherein the current flows through the element and where the same element cooperates with another element in intercapacity relation so as to form a condenser wherein the charges accu- 75

mulated are utilized for a beneficial purpose. In the modification disclosed an element has been used for supplying current to the several filaments in one circuit and at the same time cooperating with a like element in another circuit to form a condenser which functions as a by-pass from one circuit to another. The element may, for example, supply the filament of the two with direct current, a low frequency undulating current or a low frequency alternating current and at the same time cooperate with another element in a plate circuit to form a by-pass condenser for the high frequency currents from plate to filament.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific details shown, but that the means and construction herein disclosed comprises the preferred form of several modes of putting the invention into effect and the invention is, therefore, claimed in any of its forms or modifications within the legitimate and valid scope of the appended claims.

Having thus described my invention, I claim:—

- As an article of manufacture an electrical distributor-condenser unit comprising a body of dielectric material, a plurality of flat strips of electroconductive material embedded therein in parallel spaced relation, and a succession of spaced outlet taps on each of said strips extending laterally beyond the enclosing body of dielectric material at intervals throughout its length.

- As an article of manufacture, an electrical distributor-condenser unit comprising a plurality of independent electrical conductors assembled in parallel spaced relation, and a succession of spaced outlet taps on each conductor by which the conductors may be connected into independent circuits at convenient points, said conductors having an intercapacity effect between adjacent conductors of the assembly, but normally lacking direct connection with each other.

- As an article of manufacture an electrical distributor-condenser unit comprising a plurality of independent ribbon-like electrical conductors pertaining to different electrical circuits having independent sources of electrical energy inseparably arranged in fixed parallel spaced relation, said conductors having a large area so as to have a predetermined intercapacity effect and a succession of integral outlet taps on each conductor, said outlet taps pertaining to different conductors being arranged in grouped relation.

- As an article of manufacture an electrical distributor-condenser unit comprising a plurality of flat independent electrical conductor strips inseparably united in parallel spaced relation so as to have useful intercapacity effect, and a succession of outlet taps on each conductor the outlet taps pertaining to different conductors being turned in opposite directions.

- As an article of manufacture an electrical distributor condenser unit comprising a body of dielectric material, a series of flat electroconductive strips embodied therein, a succession of out-

let taps extending from each strip beyond the enclosing body of dielectric material, the outlet taps pertaining to different strips being arranged in grouped sequence repeated at intervals throughout the length of the unit.

- As an article of manufacture an electrical distributor condenser unit comprising a body of dielectric material, a series of flat electroconductive strips having useful intercapacity effect, said strips being imbedded in said dielectric material, a succession of outlet taps carried by each of the strips, the outlet taps of different strips being extended in different directions beyond the enclosing body.

- In a radio apparatus, including a source of filament and plate circuit energy, a by-pass condenser common to said filament and plate circuit leads, different conductive elements of which are connected into the filament and plate circuits respectively in which they form continuous uninterrupted line connections.

- In a radio apparatus having filament and plate circuits, including a source of filament and plate circuit energy, flat independent continuous conductor elements included in said circuits, and arranged in proximate relation to form a by-pass condenser common to the positive and negative leads of both the filament and plate circuits.

- In a radio apparatus, including independent sources of electrical energy for different circuits and a series of flat electroconductive strips arranged in inherent electrostatic relation with each other, said inherent electrostatic relation being utilized as a by-pass circuit for alternating components of the currents carried by said circuits, the positive and negative leads of each of the circuits having one of said strips included therein and forming a continuous connecting part of the current lead thereof.

- In a radio apparatus a series of instruments and parts to be interconnected, a distributor unit common to the series of instruments and parts, said unit including a plurality of electroconductors pertaining to different circuits arranged in parallel spaced relation, and a plurality of outlet taps carried by each conductor at spaced intervals whereby one of said outlet taps will be conveniently located in proximity to each of the instruments and parts to be connected thereto, said electroconductors being arranged to afford an intercapacity and electrical by-pass effect between the several circuits.

- In a radio apparatus, a series of instruments and parts to be interconnected, a duo-functional condenser conductor unit common to the series of instruments and parts, and comprising a series of electrical conductor elements arranged in fixed closely spaced relation to afford an intercapacity effect therebetween and means at spaced intervals intermediate the ends of each conductor for connecting instruments and parts at alternate points to each of the several elements of said connector-condenser which comprise component parts of different electrical circuits.

- As an article of manufacture, an electrical distributor unit comprising a series of independent electrical conductors arranged in an intercapacity relationship with each other and encased in a body of phenolic condensation material, each conductor having thereon a succession of exposed spaced taps wholly independent of and separate from the other conductors of the series by which instruments and parts may be connected to anyone or another selected conductor at different points throughout the length of the unit.

said intercapacity relationship of the conductors being utilized as a by-pass circuit from one conductor to the other.

13. In a construction of the character described, 5 the combination with a plurality of relatively fixed electrical conductors forming component parts of different electrical circuits having independent sources of electrical energy independently connected with different parts of a
- 10 radio apparatus, said conductors being so located as to have intercapacity effect upon each other of a movable condenser element adjustable relative to said relatively fixed conductors to vary the capacitive effect therebetween.
- 15 14. In a construction of the character described a plurality of independent electroconductors comprising component parts of different electrical circuits having independent sources of electrical energy, and connected with different 20 parts of a radio apparatus and arranged in grouped relation so as to have intercapacity effect upon one another, and a relatively movable element having variable capacity relation with said grouped conductors.
- 25 15. In a construction of the character described, a plurality of fixed condenser elements, and a plurality of variable condenser elements associated in capacitive relation therewith to which the fixed elements are common, different 30 members of said plurality of variable condenser elements being connected in different electrical circuits having independent sources of electrical energy.
16. In a construction of the character described, 35 a plurality of relative fixed continuous electrical connectors forming component parts of different electrical circuits having independent sources of electrical energy, and a plurality of adjustable condenser elements located in circuits different from said continuous electrical connectors and variable relative to the connectors with which they have capacitive relation and which are common thereto.
17. In a construction of the character described, 45 a plurality of electrical circuits, a plurality of adjustable condenser elements separately included in different electrical circuits and a continuous electrical connector included in a circuit other than those containing said condenser elements common to all the adjustable 50 condenser elements and having capacitive relation therewith but negligible mutual inductive coupling.
18. In a construction of the character described, 55 a plurality of electrical circuits, a plurality of swinging condenser plates and a con-
- tinuous electrical connector strip included in different electrical circuits having independent sources of electrical energy, said strip being common to all the plates and with which the plates have capacitive relation toward and from which the plates are swingingly adjustable to vary the capacitive relation therebetween, said strip having negligible mutual inductive coupling with the plates. 5
19. In a construction of the character de- 10 scribed, a group of electrical conductors arranged in capacitive relation with each other, different electrical conductors comprising line connections in different electrical circuits, having independent sources of electrical energy, and a 15 series of adjustable condenser elements included in electrical circuits other than those containing the said conductors and arranged in capacitive relation with the said electrical conductors, said group of conductor elements being common to 20 all said condenser elements. 20
20. As an article of manufacture, an electrical distributor-condenser unit comprising a body of dielectric material, a plurality of strips of electro-conductive sheet material embedded therein in 25 parallel spaced relation, and a succession of spaced outlet terminals on each of said strips extending to the exterior of the dielectric material at intervals throughout its length. 25
21. As an article of manufacture, an electric 30 distributor-condenser unit comprising a plurality of independent electrical conductors assembled in spaced relation and a succession of spaced portions on each conductor, said spaced portions being accessible from the exterior of the assembly 35 whereby the conductors may be connected into independent circuits at convenient points, said conductors having an intercapacity effect between adjacent conductors of the assembly but normally lacking direct connection with each 40 other. 40
22. In a radio receiver for a multi-element tube, an electro-conductive condenser unit including a ground strip, a plurality of ribbon-like strips arranged in intercapacity relation with respect to 45 said ground strip and separated therefrom by insulating material holding the strips in fixed relation, means for connecting said ribbon-like strips to the elements of said tube, portions of 50 said strips being accessible for connecting the elements of the tube to their respective circuits through said strips, whereby the ribbon-like strips are connected to a plurality of said tube element circuits in which circuits said ribbon-like strips form uninterrupted line connections. 55

EDMUND T. FLEWELLING.
